United States Patent Office

Des. 216,523
Patented Jan. 27, 1970

216,523

INVALID AID

Robert A. Hasty, Dallas, and William W. McKinney,
Fort Worth, Tex., assignors to N & H Instruments,
Inc., Carrollton, Tex., a corporation of Texas

Filed Apr. 8, 1969, Ser. No. 16,624

Term of patent 14 years

Int. Cl. D24—01

U.S. Cl. D83—1

FIG.-2

FIG.-1

FIG.-3

FIG.-4

FIGURE 1 is an isometric view of an invalid aid showing our new design;

FIGURE 2 is a side elevation, the opposite side being identical;

FIGURE 3 is a top plan view; and

FIGURE 4 is an end elevation with the handle support broken away for convenience of illustration.

We claim:

The ornamental design for an invalid aid, substantially as shown and described.
